D 7-581

EX

D 9532

OR

D 27,290

DESIGN.

—
L. S. IPSEN.

PLATE OR ANALOGOUS ARTICLE.

No. 27,290.

Patented July 6, 1897.

WITNESSES:

William S. Briggs.
Reuben L. Roberts.

INVENTOR:

Ludwig S. Ipsen

UNITED STATES PATENT OFFICE.

LUDVIG S. IPSEN, OF MALDEN, MASSACHUSETTS, ASSIGNOR TO THE RICHARD BRIGGS COMPANY, OF MASSACHUSETTS.

DESIGN FOR A PLATE OR ANALOGOUS ARTICLE.

SPECIFICATION forming part of Design No. 27,290, dated July 6, 1897.

Application filed January 14, 1897. Serial No. 619,256. Term of patent 7 years.

To all whom it may concern:

Be it known that I, LUDVIG S. IPSEN, a subject of the King of Denmark, residing at Malden, in the county of Middlesex and State of Massachusetts, have invented and produced a new and original Design to be used as a Decoration for Plates, Cups, and Analogous Articles of Crockery and Porcelain-Ware, of which the following is a specification, reference being had to the accompanying drawing, which shows the same as applied to a plate.

The leading features of this design consist of a border defined by two parallel ornamental lines made up of a conventional vine extending around the edge of a plate or other article to be ornamented, and in the space between these two border-lines festoons of flowers or leaves provided with a bow of ribbon at the apparent point of attachment of each curve of the festoon. Over the curve of each festoon is a conventional "fleur-de-lis," and at regular intervals around this border a shield ornamented with the fleur-de-lis is arranged upon the festoons as though hung from the point of attachment of two of its loops.

A further ornament, which may be termed a "coat of arms" and which is intended to be used in connection with the above-described border, consists of a shield ornamented with the fleur-de-lis, a crown placed at the top of the shield, and a wreath of leaves encompassing it from beneath, the whole surrounded by a circle formed of a conventional vine. This ornamental figure is to be placed in the center of dishes, like plates, as illustrated in the drawing, and upon the side of deep dishes or vessels, such as pitchers and tureens and their covers.

What I claim is—

1. In the design for plates and analogous articles of crockery and porcelain ware, a decorative border comprising two boundary-lines of leaves, festoons of flowers and leaves tied with ribbons, symmetrically arranged between said lines and shields placed at regular intervals over the festoons, substantially as set forth.

2. The decorative design for plates and analogous articles of crockery and porcelain, comprising the ornamental border and coat of arms herein described and shown.

LUDVIG S. IPSEN.

Witnesses:

WILLIAM S. BRIGGS,
REUBEN L. ROBERTS.